13 Claims. (Cl. 287—53)

1

This invention relates to a vehicle primarily intended for use as an airplane in which a section containing the power unit and the operator's controls may be separately used as an automobile.

The history of the airplane is almost as old as that of the automobile. Both appeared at approximately the turn of the century. Yet today, almost a half a century later, there are a very large number of automobiles in this country to every one privately owned airplane.

Such a condition is the result of certain basic shortcomings in the airplane. Airplanes require airports to operate. Airports are of necessity located on the outskirts of communities, not infrequently at considerable distance. Thus the time saved by the speed of aerial transportation is more frequently than not consumed by the ground-travel time required to get from the airport to the flier's final destination.

Furthermore, the expense of travel between the airport and the community, usually involving taxis, is not inconsiderable. When to this is added the initial cost and upkeep of the airplane plus that of an automobile which the flier undoubtedly owns as well, it is obvious why few can afford to own an aircraft.

The average automobile ride from point of origin to destination is not over five miles. For every automobile trip of several hundred miles, the average man makes as many as a hundred short local trips. Since he can afford only an automobile or an airplane, his choice is obvious.

This has been the basic factor in retarding widespread public adoption of the airplane in the past and, unless remedied, will have a serious effect on its future. Various endeavors have been made to circumvent the situation. Closer-to-town airports, locally available cars for rent, and other expedients have been offered but they fail to solve the basic practical and economic problems.

While the real cure has been much discussed, little or nothing of a practical nature has been executed to carry it into effect. Obviously there is much in common between an automobile and an airplane. Both have wheels, a body, a cab or cabin, a motor, and controls for starting, guiding and stopping. When a pilot leaves his aircraft at an airport and takes a cab to town he is leaving behind 90% of the basic elements of an automobile—an expensive and unnecessary procedure which has done more than any other thing to stifle aviation.

Others have recognized this fundamental prob-

2

lem and have made efforts to solve it by accomplishing a transition from airplane to car and back. But the problem has many aspects—mechanical, aerodynamic, practical, safety, economy, comfort, service and maintenance, public reaction and acceptance. Of the several suggested solutions which have been offered to date, all have failed due to neglect of one or more of the above features. Most have been so radical in conception and based on such untried principles that they have failed to hold public interest. Others have made contributions which, unless supplemented by many additional features, were of little practical value.

15 It is an object of this invention to produce a roadable airplane by making a practical combination of already accepted forms and styles of automobile and aircraft designs, thereby making the final unit one of greater public value by a combination of already familiar elements.

The present invention therefore is concerned with an airplane having a removable section adapted for use as a standard automobile and an airplane section comprised of wings, fuselage 25 and flight control surfaces, and having cooperating interlocking means on the airplane and automobile sections by which the sections may be firmly held together to establish a complete airplane. When the automobile section and airplane section are combined for flight, the resulting airplane is to be driven through the air by a screw propeller. When, however, the automobile section is used alone for road travel, the propeller is not relied upon to cause motion and as it therefore has no utility it is desirable to remove it. Removal of the propeller from the automobile section during road travel is important because it would detract from the good appearance of the automobile and because its presence would constitute an objectionable safety hazard.

35 Inasmuch as the propeller is to be affixed in place to drive the airplane when the automobile and airplane sections are combined for air flight, and must be removed when the automobile section is to be used alone and this changeover may occur several times during one day, it is important that the propeller be easily removable from and connectable to the engine. The present invention provides a propeller attachment means which is readily disconnectable.

Moreover, as a feature of the invention, the propeller attachment means includes a provision for locating the propeller in such position on the shaft that the propeller will be at the customary angle for turning it over by hand to start the

engine. When the engine is shut off after running and the motor comes to rest, the propeller either will be in the proper position to be pulled down to start the engine or can be brought to that position by turning the propeller.

In order that the propeller may be firmly affixed in place it is necessary that a tool be used to give a mechanical advantage. For example, if, as in the present instance, the propeller is held in place by a screw threaded connection, a wrench should be employed to tighten this connection and hold the propeller firmly in place. Inasmuch as the propeller may be removed and replaced several times in each day, it is important that this wrench be always available. The invention therefore contemplates the employment of a wrench which is permanently attached to the propeller so that it cannot become displaced from the propeller and is always immediately at hand for use.

As a further feature of the invention, the wrench which is carried by the propeller is movable to an out-of-the-way position when it is not being used. The invention therefore contemplates a telescopic lever which may be withdrawn to an operative position.

Another feature of the invention is the provision of the lever with a self-contained gauge to indicate the proper degree of tightening of the screw-threaded connection. This is important to make sure that the screw-threaded attachment is sufficiently tight to hold the propeller firmly in place and also to prevent the possibility of over-tightening and possible stripping of threads. In accordance with the invention, the lever is provided with a device which visually indicates the extent to which the propeller has been tightened in place.

A further feature of the invention is the employment of a locking means which assures the retention of the propeller in place. This locking means is preferably an easily movable element which exerts a control through successively stronger elements to retain in place the screw attachment which holds the propeller in a fixed position.

Another feature of the invention is the employment of a cap or spinner member which may be used either in front of the hub of the propeller when it is in place, or to enclose the projecting shaft when the propeller is removed therefrom.

Although the invention has particular utility in connection with a roadable airplane inasmuch as such an installation calls for repeated removals and replacements of the propeller, it is to be understood that the invention is not limited to such use since it may be applied to an airplane which is intended to be used only for air travel. For example, the invention can be employed with a standard airplane inasmuch as its propeller can be attached by the structure of this invention and this will have the advantage of making it possible to readily remove and replace the propeller in service.

Other features of the invention will be evident from the following description and from the drawings which disclose a preferred structural embodiment of the invention.

In the drawings:

Figure 1 is a side elevation of the airplane as it appears when the automobile and airplane sections are assembled for flight;

Figure 2 shows the automobile section removed from the airplane section and the airplane sec-

tion in its self-sustaining position, the propeller being removed from the automobile section and being housed within the airplane section;

Figure 3 is a section passing through the axis of the supporting shaft, the propeller being affixed thereto as in Figure 1;

Figure 4 is a view similar to Figure 3 but showing the propeller partly removed from its supporting shaft;

Figure 5 is a front elevation of Figure 4;

Figure 6 is a section on the line 6—6 of Figure 4, through the lower portion of the lever;

Figure 7 is a front elevation of Figure 3 the cover cap, however, being removed;

Figure 8 is a section on the line 8—8 of Figure 3;

Figure 9 is a section on the line 9—9 of Figure 4;

Figure 10 is a fragmentary side elevation of the meeting line between the removable cover cap and the propeller hub at a right angular turn from the plane of Figure 3;

Figure 11 is a section on the line 11—11 of Figure 10;

Figure 12 is a section on the line 12—12 of Figure 4;

Figure 13 is a section passing through the axis of the supporting shaft with the propeller removed, as in Figure 2;

Figure 14 is a front elevation of Figure 13, with the cap removed;

Figure 15 is a side elevation similar to Figure 4 but showing a modified form of lever;

Figure 16 is a front elevation of the lever of Figure 15;

Figure 17 is a section on the line 17—17 of Figure 16; and

Figure 18 is a fragmentary view showing the swivel block at the end of the lever of Figure 15, in an extended position.

The roadable airplane to which the invention is here shown applied is of the character generally represented in application Serial No. 580,842, now Patent 2,430,869 dated November 18, 1947. However, it will be understood that the invention is not to be limited in this respect as it may be applied to any other type of roadable airplane and as has been stated may in fact be applied to the propeller of a standard airplane.

Referring first to Figure 1, the automobile section 1 of the airplane appears at the left of the vehicle and the airplane section 2 appears at the right of the vehicle. In Figure 1 these two sections are combined for flight and in Figure 2 they are separated from each other so that the automobile section may be driven independently as a unit for road travel. When the automobile section is used as a unit the airplane section 2 is left behind.

The airplane section 2 includes lifting wings 3 at its forward portion and at the trailing edges of these wings are the usual ailerons 4. At the rear of the airplane section are the usual control surfaces and these include the rudder 5 and the elevators 6. Beneath these tail surfaces is a landing wheel 7.

When the airplane section is attached to the automobile section as shown in Figure 1, the airplane section is supported as a cantilever as shown in Figure 1. The means for attaching these sections together and by which the sections may be released from each other constitute no part of the present invention and consequently are not shown in detail. A suitable means is disclosed in application Serial No. 580,844, filed on

March 3, 1945. When this interconnecting means is released and the sections are separated from each other, the airplane section must be self-supporting and to accomplish this it is provided with wheels 8 beneath the forward wings.

Just prior to the time that the airplane section is separated from the automobile section, the wheels 8 and the landing wheel 7 are moved downwardly into contact with the ground. The means by which the wheels 7 and 8 are moved downwardly are not a part of the present invention and therefore are not here described in detail, but suitable means is disclosed in application Serial No. 580,843, filed on March 3, 1945. These wheels 7 and 8 support the airplane section in the same position which it would occupy if it were attached to the automobile section so that separation of the sections and their reconnection is facilitated.

The automobile section 1 includes the front wheels 10 and the rear wheels 11. It also includes a motor 13 to which the propeller 14 may be attached for air travel as shown in Figure 1, or from which it may be removed for road travel as shown in Figure 2. The propeller 14 which is here shown is a conventional wooden propeller but it is to be understood that the invention may be applied equally as well to a propeller having metal blades and a metal hub.

The conventional hub as is here shown has an axial bore 15 to receive the forward end of a drive shaft 16. This drive shaft 16 here shown is the crank shaft of the engine 13, but it is apparent that it might as well be a separate shaft driven by the engine. Rearwardly from the forward end of the shaft 16 is a flange 17 and a plurality of circularly arranged holes 18 (Fig. 14) are therethrough adjacent to the periphery of the flange. These holes are evenly spaced and as here shown there are six of these holes, but this number is not essential. The flange 17 is also formed with holes 19 to reduce the weight of the flange.

The drive shaft 16 is formed with an axial bore 21 (Figs. 3, 13) entering from the forward end of the shaft. At its forward end the shaft is formed with internal threads 22 and at the entrance portion of these threads is a slight enlargement at 23 (Fig. 13) to form a guide leading to the threads.

Passing through the hub of the propeller 14 are a plurality of bolts 24. As is best shown in Figure 5, the bolts 24 are located in two pairs and each pair is disposed toward the blades of the propeller. The bolts 24 are thirty degrees to each side of a plane passing lengthwise through the centers of the propeller blades, to conform to the spacing of the openings 18. If desired more or fewer than four bolts 24 may be employed but it has been found in practice that these four bolts are satisfactory to establish a driving connection between the propeller and the flange 17.

The bolts 24 also serve to clamp face plates against the opposite sides of the hub of the propeller. An annular plate 25 is clamped to the rear face of the propeller and this plate 25 is recessed to receive flanged enlargements 26 of the bolts 24. Beyond the flanges 26 the bolts 24 have a cylindrical extension 27, terminating in a pointed end 28. This pointed end 28 makes it more easy to accomplish the entry of the bolt portions 27 into the openings 18 of the flange 17.

One of the projections 27 may be of larger diameter as shown at 27' in Figure 12 and an

opposite pair of the openings 18 is large enough as shown at 18' in Figure 14 to receive this projection. This makes it possible to put the propeller on the shaft in only one angular position and this should be such as to locate the propeller so that it may be pulled down upon to start the engine. When the engine comes to rest after being shut off, the propeller will be in the right position for starting or can readily be brought to that position by turning the propeller.

The internal diameter of annular plate 25 conforms to the outer diameter of the shaft 16 over which it fits so that radial movement of the propeller relative to the shaft 16 will be further prevented by this fit. However, the internal diameter of annular plate 25 may be slightly larger than shaft 16 so that bolts 24 are relied upon to center the propeller. The bore 15 through the hub of the propeller should preferably be slightly larger than this internal opening through the annular plate 25 so that the wooden part of the propeller is not relied upon to center it.

To the forward face of the propeller 14 are clamped an annular plate 30 and a ring 31. Nuts upon the projecting ends of the bolts 24 serve to affix plate 30 and ring 31 in this position. The ring 31 is formed with a plurality of openings 32 close to its central opening, but these openings 32 do not extend entirely around the ring 31, for a purpose to be later explained. The rearward face of the ring 31 is formed with a counterbore 33 (Figures 3, 4) of larger diameter than the central opening in annular plate 30 so that a socket is formed to receive a flange 34 of a screw member 35.

The screw member 35 is of tubular shape and has external threads 36 at one end to engage with the internal threads 22 of shaft 16. Flange 34 is held in place between the rings 30 and 31 because of its entry into the recess 33 and therefore axial movement of the screw member 35 with respect to the propeller is prevented. Rotational movement of the screw member 35 within the propeller 14 is permitted so that the screw member 35 may be threaded into shaft 16 without causing rotation of the propeller 14, to draw the propeller against flange 17.

Through the flange 34 are formed a plurality of uniformly spaced circumferentially disposed openings 37. There may be any desired number of the openings 37 but it is important that they be in diametrically disposed pairs and as here shown there are eight pairs. It is desirable, as will be later explained, that the openings 37 in flange 34 be spaced apart differently from the openings 32 in flange 31.

When the screw member 35 is threaded into the shaft 16 it carries the propeller 14 along the shaft so that the annular plate 25 is brought firmly against the flange 17 of the shaft. The projecting portions 27 of the bolts 24 may enter any corresponding four ones of the holes 18 in the flange 17 during this movement. Pressure of the flange 34 against the annular plate 30 retains the propeller in place upon the shaft 16. When the screw member 35 is unscrewed from the shaft 16, the flange 34 bears against the ring 31 and withdraws the propeller from the shaft 16 to the position of Figure 4.

The threads 36 enter within shaft 16 a sufficiently short distance that when the screw member 35 is completely unscrewed therefrom as is shown in Figure 4, the propeller is not fully drawn off of the shaft 16. As is evident from Fig-

ure 4, the complete withdrawal of the screw member 35 from the shaft 16 is sufficient to remove the ends 27 of bolts 24 from openings 18 so that the propeller is free upon the shaft. However, the propeller is still upon a sufficient portion of the end of shaft 16 so that the propeller will remain supported on the shaft and will not fall off.

After the screw member 35 is fully threaded into the shaft 16, it is important that the screw member 35 is locked against rotational movement so that it cannot become unscrewed. The screw member 35 is locked against rotational movement by means of a forked locking member 40. Locking member 40 is provided with two pins 41 which are diametrically disposed from each other a distance equal to the diametrical spacing of the openings 32 and 31. Insertion of the pins 41 into the registering openings 32 and 31 prevents rotation of flange 34 and consequently prevents screw member 35 from unscrewing. The locking pins 41 therefore connect the flange 34 to the ring 31 and since the bolts 24 engage within the openings 18 of flange 17, the flange 34 is in effect locked to the shaft 16 so that the screw member 35 cannot unscrew.

From Figure 3 it will be noted that the central opening within annular plate 30 is sufficiently large to not obstruct the passage of pins 41 through the openings 31. The pins 41 may therefore be inserted fully through the openings 32 and 31 to make sure that a strong connection is established.

It has been noted that the openings 32 are spaced apart slightly differently from the spacing of openings 31. As here illustrated, the openings 32 are further apart than the openings 31 an angular distance of seven and one-half degrees. When the screw member 35 is fully drawn into the shaft 16, one diametrically related pair of the openings 32 will therefore be within less than four degrees of registration with a diametrical pair of openings 31.

It is not necessary that openings 32 be continuous around the ring 31 inasmuch as this would mean merely a duplication of the registration of openings 32 and 31. It is therefore sufficient to have only enough of the openings 32 to avoid such a duplication and it is for this reason that openings 32 do not extend around a continuous circle in Figure 7. It is important however that the openings 32 be in diametrical pairs to receive both pins 41.

The invention contemplates the provision of a lever to rotate the screw member 35 and advantageously this lever shall be permanently connected to the propeller so that it will always be available for use in rotating the screw member 35 and cannot become mislaid. For this purpose a lever 42 is provided and to obtain a leverage effect it is positioned in a notch 43 in the side wall of the screw member 35 so that it extends at a right angle to the axis of screw member 35 as appears from Figures 4 and 5. When the lever is in this position it may be turned to rotate the screw member 35 in either direction.

When the lever 42 is not being used to turn the screw member 35, it is brought out of notch 43 and into line with the axis of screw member 35 and then inserted into the bore within the screw member 35 and the bore 21 of the shaft 16. This telescopic position of lever 42 is shown in Figure 3, and this arrangement constitutes an important feature of the invention as the lever is in a remote and yet readily available location.

To facilitate grasping the lever 42 to withdraw it from the position of Figure 3, the forked member 40 is formed with lugs 44 (Figs. 5, 6) to be engaged by the fingers.

To the inner end of lever 42 is attached a block 45 by means of a pivot pin 46. The block 45 closely fits the interior bore of the screw member 35 (Fig. 4) to serve as a guide. Also, when the lever 42 is pressed upon, the block 45 transmits the turning force to the inner wall of screw member 35.

Outward movement of the lever 42 and its attached block 45 is prevented by means of a retaining ring 47 seated in a groove within the screw member 35 and against which the block 45 strikes as a stop. When the block 45 is brought against this ring 47, the lever 42 may be turned about its pivot 46 and be brought into the notch 43 in the end of the screw member 35 so that the lever 42 extends at right angles to the axis of the screw member 35.

The forked locking member 40 is attached to the outermost end of lever 42 so that this locking member 40 cannot become detached from the propeller 14 and is therefore always available for use in locking the propeller in place. In addition, the locking member 40 serves as a handle at the end of the lever 42 to make it more convenient to bear upon the lever 42 in rotating it.

When the lever 42 is telescoped within the shaft as shown in Figure 3, it is desirable that the block 45 be held in axial alignment with the lever 42 so that the block 45 will not drop down into such a position that it might be difficult to bring it into the interior of screw member 35. For this purpose, a spring pressed ball 48 is located in the block 45 and it is urged against a depression 49 in the end of lever 42. In the position of Figure 3, the pressure of ball 48 in the depression 49 holds the block 45 in axial alignment with the lever 42.

An important feature of the invention is the construction of the lever 42 in such manner that it will serve as an indicator of the firmness to which the propeller 14 has been forced into place. In the construction illustrated in Figures 4, 5 and 6 this object is accomplished by forming the lever 42 of a spring construction so that the lever will flex under the turning force required to screw the propeller tightly into place, and means are provided to indicate the extent to which this lever must be flexed to make certain that the screw member 35 is sufficiently screwed into place.

As is best shown in Figures 5 and 6, the lever 42 is made up of a plurality of spring leaves 51 which lie flat against each other and extend throughout the length of the lever. These leaves lie in planes which are perpendicular to the force to be applied to cause rotation of the screw member 35. On the rearward side of lever 42, with respect to the direction of rotation when the screw member 35 is being screwed in place, are two leaf portions 52 and 53. The leaf portion 53 is slightly longer than the leaf portion 52 so that the portion 53 slightly overlies the end of the leaf portion 52.

When the lever 42 is urged in a clockwise direction, as viewed in Figure 5, to tighten the screw member 35, it flexes to a position generally indicated by the dot-and-dash line at the lower portion of Figure 5. This causes a bending of the lever to such an extent that the leaf portion 52 draws away from the leaf portion 53 and the extent of overlap becomes gradually diminished as the flexing of the lever increases. When the

lever has been urged upon hard enough to draw the propeller 14 tightly in place, the leaf portions 52 and 53 should be so far withdrawn from each other that the leaf portion 53 will drop off of the edge of leaf portion 52 and become in line with leaf portion 52.

When the leaf portions 52 and 53 come in this edge-to-edge position for them to be in alignment, the snapping of the leaf portion 53 off of the edge of leaf portion 52 will make an audible sound which will indicate that the screw member 35 has been drawn sufficiently tightly in place. The person applying the propeller will therefore know that it is tightly held in place and that it is not necessary to exert any further effort. Also, he is informed that any further tightening is not desirable as it might bring about a possible stripping of the threads 22 or 36 or cause some other damage.

It is not necessary to rely upon the audible sound made by the snapping of the spring portion 53 over the adjacent edge of spring portion 52 as the lever may be urged to a certain extent and then be released to see whether the spring portions 52 and 53 have come into alignment. When the lever has been urged strongly enough for this alignment to occur and the lever is then released, the pressure of the end of leaf portion 52 against the abutting end of leaf portion 53 will cause the leaf portion 53 to bow outwardly, as is shown in dotted lines in Figure 5. Leaf portion 53 is made highly resilient so that it will easily flex in this manner. The operator may therefore continue to tighten and release the lever until he observes this flexing of leaf portion 53 which indicates that he has sufficiently tightened the screw member 35.

To restore the leaf portions 52 and 53 to their relationship shown in full lines in Figure 5, a sharpened instrument, as a screw driver, may be employed to press upon leaf portion 53 and urge its free end outwardly and upon leaf portion 52. Or, the clip 56 may be manually pressed upon to push the free end of leaf portion 53 away from leaf portion 52 so that they may reassume the positions in full lines in Figure 5.

The several leaves 51 and 53 are pivoted at their adjacent ends upon the pin 46 as has been explained in reference to lever 42. The forked locking member 40 is pinned by a rivet 54 (Figure 6) only to the leaf portion 52 and to the next adjacent one of the leaves 51. All of these leaves lie in a socket 55 within locking member 40 and as is shown in Figure 6 the leaves 51 are progressively shorter in a direction away from the leaf portion 52 so that until the lever is flexed under the force required to tighten the screw member 35 these leaves will not strike the bottom of the socket 55 and limit the free flexing of the lever 42.

A clip 56 is attached, as by a rivet 57, to the leaf portion 52 slightly inwardly from its free end. This clip 56 is not attached to the leaves 51 as such a construction would prevent the free flexing of the lever 52. The clip 56 retains the leaf portion 52 in place on top of the leaves 51 and against sidewise displacement. A similar clip 58 is riveted to leaf portion 53 to prevent its sidewise displacement.

It will be appreciated that the lever 42 must be so positioned in notch 43 that when the lever is moved in a clockwise direction to tighten screw member 35, the leaf portions 52, 53 will be on the trailing side of the lever. Thus, if the lever were turned about pivot 46, when it is being brought in notch 43, in such a direction as to bring leaf

portions 52, 53 on the leading side of the lever, the indicating means would be inoperative. To make sure that the lever 42 can be pivoted around pin 46 only in the proper direction, its end is rounded off at 59 only at one corner. The other corner is left square to serve as a stop which will strike the block 45 and prevent turning of lever 42 about pivot 46 in the wrong direction.

It is important that the locking member 40 be retained in the position of Figure 3 so that the pins 41 will be maintained in their locking positions in the registering openings 32 and 37. If the locking member 40 could move away from the position of Figure 3, the vibration of the airplane might cause the screw member 35 to loosen and possibly ultimately permit the propeller 14 to fall off. If locking pins 41 remain in the openings 32 and 37, the propeller will be maintained in place.

In accordance with the invention, the locking member 40 is retained in locking position by the control exerted through successively weaker elements so that a simple lock may ultimately be employed. The invention furthermore contemplates the association of this lock with a cover or cap which encloses the working parts on the front side of the propeller hub, so that this cap is retained in place by the lock. The lock is intended to be available from the exterior of this cap.

To retain the locking member 40 in the position of Figure 3, a bail 60 is pivoted at its ends upon pins 61 carried by the ring 31. Pins 61 are diametrically related so that in the distended position of Figure 3, the bail 60 passes over the axis of the propeller. Welded to the bail 60 in position to overlie the center of the locking member 40 is a post 62. Post 62 is formed with a reduced extension 63 which may be snapped into a depression 64 in the end of locking member 40. The flexing of the bail 60 will be sufficient to permit the post 62 to yield outwardly as it rides over the curved outer end of locking member 40 until the depression 64 is reached. The tension 45 which exists in bail 60 when its projecting end 63 is in the depression 64 is sufficient to maintain it in this relationship so that the locking member 40 will be held in its inner position and this may alone be relied upon. However, the invention 50 contemplates the provision of additional means for assuring that the post 62 cannot become displaced from the position of Figure 3.

To more positively maintain post 62 in the position of Figure 3, it is formed with an internally threaded recess 65 into which may be screwed a threaded extension 66 of the rotating barrel of a lock 67. The outer shell of lock 67 is positioned for endwise movement within a socketed body 68. Bolts 69 attach this socketed body 68 to a cap or spinner member 70 which serves to cover the elements at the hub of the propeller.

A spring 72 within the socket of body 68 serves to urge the lock 67 to an outer position but the lock 67 is prevented from complete outward movement by attaching to its shell a ring 73 having diametrical lugs 74 which extend into slots 75 lengthwise along the body 68. The contact of these lugs 74 against opposite end walls of the slots 75, limits the movement of the lock 67. Also, the engagement of lugs 74 in slots 75 prevents rotation of the shell of the lock.

When the cap 70 is brought into position against the propeller hub, the lock 67 is in axial alignment with the threaded bore 65 of post 62

11

and the threaded projection 66 will therefore enter into this threaded bore. Rotation of the inner barrel of lock 67 by means of the key 76 will cause the threaded part 66 to screw into the threads of the bore 65 and this inward movement of the lock 67 is permitted by the compression of the spring 72 and sliding of lugs 74 along slots 75. The key 76 is turned until the threaded part 66 has been screwed several times within the bore 65. To visually indicate that the part 66 is sufficiently screwed in place, the parts may be so related that the outer face of the lock becomes flush with the nose of cap 70 as shown in Figure 3. Spring 72 should be sufficiently weak that it will have a negligible tendency to withdraw the projection 63 from the depression 64.

After the threaded part 66 is screwed several turns into the post 62, the key 76 will be withdrawn and thereafter rotation of the lock barrel and of screw 66 attached thereto will be prevented. As the threaded part 66 will remain screwed into post 65, the bail 60 cannot move out of position but will retain locking member 40 in the position of Figure 3. As the screw 66 can be turned only by use of the key 76, it is apparent that the mechanism may not be tampered with by an unauthorized person. Complete assurance is had therefore that the propeller is firmly held in position although the operator has not been constantly present.

The cap 70 fits at its open end upon a central shell which encloses the hub of the propeller 14. This shell includes a front plate 80 (Figures 3 and 4), the center of which is clamped against the hub beneath the annular plate 30. The outer periphery of plate 80 is turned inwardly toward the propeller to form a generally cylindrical flange 81. On the rearward side of the hub of the propeller is a plate 82, the central portion of which is secured to the annular plate 25 by attachment bolts 83 (Figure 12). The outer periphery of plate 82 is flanged at 84 to constitute a substantially cylindrical portion.

Between the flanged portion 81 of plate 80 and the flanged portion 84 of plate 82 is a cylindrical sleeve 85 which completely interconnects them except at the location of the blades 14. This sleeve 85 is split at the blades to permit its location in place. The sleeve 85 is attached by rivets or other suitable means to the flanges 81 and 84.

As is shown in Figure 3, the sleeve 85 occupies only the rearward portion of the inturned flange 81 of plate 80. The open end of cap 70 seats upon the remaining forward portion of the inturned flange 81 as a seat. As is also apparent from Figure 3, the outer surface of cap 70 forms a substantially flush surface with the outer surface of sleeve 85 so that a smooth appearance is presented.

To prevent rotation of cap 70 upon the flange 81, it is formed with a notch 86 (Figures 10, 11) which fit over a headed pin 87 (Figure 5) attached to the flange 81 of plate 80. This prevents rotation of cap 70 and therefore prevents rotational movement of the socketed body 68 such as would turn the shell of lock 67 and cause the threaded part 66 to unscrew from lug 62.

The threaded engagement between lock 67 and post 62 therefore not only maintains the post 62 in the retaining position of Figure 3, but also maintains the cap 70 in place. The cap 70 can not become loosened since the lock 67 can be unscrewed only by means of key 76. The cap 70 will therefore remain in place to cover and protect the parts on the front of the propeller hub.

12

Cap 70 is also used to cover the shaft 16 after the propeller has been removed therefrom. When the automobile section 2 is used alone as an automobile the front of the engine cowling or hood, 5 has the appearance shown in Figures 2 and 13 so that a pleasing appearance is made.

The cowling 90 which encloses the engine has a substantially flat front plate portion 91 (Figures 13, 14) having an opening 92 therein through 10 which the engine shaft 16 projects. Secured to this front flat portion 91 is a ring 93 concentrically located with respect to the axis 19. The exterior of the ring 93 is of a size to snugly receive thereover the open end of the cap 70, as is 15 shown in Figure 13.

To retain the cap 70 in position on the ring 93 a bail 94 is provided. The ends of bail 94 are turned inwardly toward each other (Figure 14) and are bearinged in clips 95 which are secured 20 to the front plate 91. Attached to the central part of the bail 94 is a post 96 which is internally threaded to receive the threaded portion 66 of lock 67. The lug 96 is so positioned that when the cap 70 is brought into place the screw portion 66 25 may be threaded into the post 96 by rotation of the key 76.

Inasmuch as it would be difficult to manually hold the post 96 and bail 94 in proper position when the cap 70 is being brought into place, it is 30 desirable to provide stop means to limit the downward movement of bail 94 to the position of Figure 13. For this purpose the ends of the bail 94 adjacent to the bearing clips 95 are formed with stop lugs 97. These lugs 97 strike the front 35 plate 91, as shown in Figure 13, and prevent further downward movement of bail 94. When the cap 70 is brought upon ring 93, post 96 is therefore in position to receive the threaded part 66.

When the propeller is to be affixed on the shaft 40 16, cap 70 is removed by unscrewing lock 67 by key 76. Then the bail 94 is pivoted upwardly and the post 96 enters opening 98 in the front plate 91. The post 96 moves partly past the wall 91, through opening 98, so as to lock behind the 45 wall 91 as shown in Figure 13, to serve to retain the bail 94 in its collapsed position, but other suitable means may be employed to hold the bail in this position.

As appears from Figure 14, the bearing clips 95 50 are positioned below a diametrical horizontal plane through the shaft axis 16. This is desirable because if the clips 95 were located directly aside of the axis of shaft 16, the bail 94 would have to be of such length to extend outwardly to the 55 threaded portion 66 of lock 67 that in its upright collapsed position the post 96 would project beyond the top of ring 93. By moving the clips 95 downwardly to a position such as is shown in Figure 14, the bail 94 may be sufficiently long and when it is moved upwardly the post 96 will remain within the ring 93.

When the propeller is removed from the shaft 60 16 it may be stored in any desired place. One such suitable place is within the interior of the airplane section as appears in Figure 2. For this purpose, the airplane section may have a rack or shelf to receive the propeller. The propeller is then available with the airplane section to make the complete airplane of Figure 1.

In the embodiment of Figures 15 to 18, inclusive, a modified construction of the lever is 70 illustrated. In this instance, a different indicating means is employed to inform the operator that the screw member 35 has been sufficiently tightened into place.

This lever is made up of a plurality of leaves 100 and as in the case of the lever illustrated in Figures 5 and 6, these leaves are disposed to flex flatwise when the screw member 35' is being tightened. Screw member 35' is identical to screw member 35 of Figures 4 and 5. Upon the side of the lever away from the direction of rotation is a leaf portion 101. This leaf portion 101 and the one of the leaves 100 next adjacent thereto is clamped by a rivet 102 within a socket of the locking member 40'. This locking member 40' is the same as the member 40 illustrated in Figures 4 and 5.

The leaves 100 are pivoted upon the pin 46' of the block 45'. The end faces of these leaves 100 are formed with a depression 103 corresponding to the depression 49 in Figure 4 to receive the spring urged ball 48'. Also, one corner only of the ends of leaves 100 is rounded off at 104 to permit the turning movement of the lever about pivot pin 46' in only one direction. This rounded edge at 104 corresponds to the rounded edge 59 in Figure 4. This shoulder 104 makes it impossible to pivot the lever about pin 46' to the position which would make the indicating means inoperative when the lever is brought into notch 43'.

Attached to the end of leaf portion 101 is a clip 105. The ends of this clip are long enough to completely encircle the leaves 100 and the ends of the clip are inturned as shown in Figure 17 to form points 106. The distance between the points 106 is slightly less than the width of the leaves 100 so that if the clip 105 is drawn along the sides of the leaves the points 106 will lodge in the grooves between the leaves and remain there.

When the lever is urged upon to tighten the screw member 35' the lever will flex in the direction indicated by the arrow at the bottom of Figure 16, but the leaf portion 101 will not flex since its upper end is not held upon the pin 46'. Leaf portion 101 will therefore tend to remain straight and to carry the clip 105 along the leaves 100. The extent of pressure applied to the locking portion 40', which serves as a handle, will determine not only the tightness of the screw member 35 but will determine the position of the points 106 in the grooves between the leaves.

As the points 106 will remain in the position along the width of the lever to which they are carried in the manner which has been described, the person tightening the propeller in place need merely exert a pull on the lever, then release the lever and then observe the location of the points 106 in the position to which they have come to rest. Thus it may be known that it is necessary to tighten the screw member 35 until the points 106 come to rest in the groove between the leaf next to leaf portion 101 and the one next thereto. Thereafter the clip 105 may be pressed upon to return it to the full-line position of Figure 16.

What is claimed is:

1. In combination, a drive shaft having a flange spaced from one end thereof, said flange having openings extending therethrough in a direction parallel to the axis of the shaft, a hub having an axial opening to receive said end of the drive shaft, bolts attached to said hub and having projecting portions to enter the openings in said flange and establish a driving connection between the hub and shaft, a pair of annular plates attached by said bolts to the opposite side of the hub from said projecting portions, one of said annular plates having its inner surface cut away to pro-

vide an inwardly facing recess between the annular plates, and a member having an external flange entering into said recess and having a screw threaded connection with said shaft.

2. In combination, a drive shaft, a hub having an axial opening to receive said drive shaft, a member having a screw threaded connection with the drive shaft and having a flange overlying the end face of the hub to draw it on the shaft, said flange having an opening therethrough, a plate attached to the hub and having an opening therethrough to register with said flange opening, and a pin positioned in said registering openings to lock said member against rotation.

3. In combination, a drive shaft, a hub having an axial opening to receive said drive shaft, a member having a screw threaded connection with the drive shaft and having a flange overlying the end face of the hub to draw it on the shaft, said flange having a plurality of arcuately arranged openings therethrough, a plate attached to the hub and having a plurality of arcuately arranged openings therethrough, the spacing of said plate openings being different from the spacing of said flange openings, whereby a plate opening and flange opening may be brought into registration upon a slight turning of said member, and a pin positionable in the registering openings to lock said member against rotation.

4. In combination, a drive shaft, a hub having an axial opening to receive said shaft, a member having a portion entering the hub opening and having a threaded engagement with the shaft, said member also having a flange exteriorly of the hub and having arcuately arranged openings therethrough, and a pair of annular plates attached to the hub and having a recess between them in which said flange is disposed whereby the hub will be carried with said member as the member is screwed into or out of said shaft, one of said annular plates having a plurality of arcuately arranged openings therethrough, a diametrically disposed pair of which will be brought into registry with a corresponding pair of flange openings, and a forked member having a pair of pins positionable in said pair of registering openings to lock said member against rotation.

5. In combination, a drive shaft, a hub having an axial opening to receive said shaft, means carried by said hub and having a second opening therein parallel to said axial opening in said hub, a screw member having a threaded connection with the shaft and having a flange overlying the hub-carried means to hold the hub on the shaft, said flange having an opening therethrough to register with the second opening in the hub-carried means, a pinned member having a pin portion positioned in said registering openings to prevent rotation of said screw member, and a bail attached at its ends to said hub-carried means and bearing at its central portion upon said pinned member to retain said pin portion in said registering openings.

6. In combination, a drive shaft, a hub having an axial opening to receive said shaft, means carried by said hub and having a second opening therein parallel to said axial opening in said hub, a screw member having a threaded connection with the shaft and having a flange overlying the hub-carried means to hold the hub on the shaft, said flange having an opening therethrough to register with the second opening in the hub-carried means, a pinned member having a pin portion positioned in said registering openings to prevent rotation of said screw mem-

ber, a bail attached at its ends to said hub-carried means and having at its central portion a post which bears upon said pinned member to retain said pin portion in said registering openings, and a cover supported by the hub and engaging with said post to hold the bail in its pin retaining position.

7. In combination, a drive shaft, a hub having an axial opening to receive said shaft and a second opening parallel to said axial opening, interengaging means between the hub and shaft to drive the hub with the shaft, a screw member having a threaded connection with the shaft and having a flange overlying the hub to hold the hub on the shaft, said flange having an opening therethrough to register with the second opening in the hub, a pinned member having a pin portion positioned in said registering openings to prevent rotation of said screw member, a bail attached at its ends to said hub and having at its central portion a post which bears upon said pinned member to retain said pin portion in said registering openings, a cap enclosing the front side of the hub including said flange, and a rotatable lock carried by said cap and having screw threaded connection with said post to hold the bail in its pin retaining position.

8. In combination, a drive shaft, a hub having an axial opening to receive said shaft, interengaging means between the hub and shaft to drive the hub with the shaft, a screw member threaded into said shaft and having a flange bearing upon the hub to retain the hub on the shaft, a removable pin engageable with said flange and with the hub to prevent rotation of the screw member, a cap enclosing the front side of the hub including said flange, and a lock carried by the cap and having a connection to said removable pin to hold the pin in its flange locking position.

9. In combination, a drive shaft having an external flange spaced from an end thereof, a hub having an axial bore receiving the projecting end of the shaft, means establishing a driving connection between the hub and shaft, and a screw member having a portion extending into the axial bore of the hub and threading with the shaft and also having a flange, and means carried by said hub, said screw member flange bearing against said hub-carried means to hold the hub against the shaft flange, the threaded engagement between said member and shaft being of less axial length than the length of the axial bore whereby the hub will be supported upon the shaft when the member and shaft are out of threaded engagement.

10. In combination, a drive shaft having an axial bore entering from one end thereof, a hub to be driven by said shaft and having an axial bore therethrough, means establishing a driving connection between the hub and shaft, a means carried by said hub, a hollow screw member having threaded engagement with the shaft and also having a portion bearing on the hub-carried means to hold the hub on the shaft, and a lever engageable with said screw member in an active position at right angles to the axis of the member to effect rotation of the member, and movable to a telescopic position within said

hollow member and the hub and shaft bores when the lever is to be inactive.

11. In combination, a drive shaft, a hub to be driven by said shaft and having an axial bore therethrough, means establishing a driving connection between the hub and shaft, a hollow screw member having an external flange between its ends, the portion of said screw member projecting from said flange in one direction threadedly engaging with the shaft and the portion of said screw member projecting from said flange in the other direction being provided with a notched sidewall, and a lever positionable in said notch and at right angles to the axis of the member to effect rotation of the member, and also positionable telescopically within said hollow member when not in use.

12. In combination, a drive shaft, a hub having an axial bore receiving said shaft therein, means establishing a driving connection between the hub and shaft, a hollow screw member having a screw threaded connection with the shaft and having an external portion, a means carried by said hub, said screw member external portion bearing against said hub-carried means to hold said hub on the shaft, and a lever having an inactive position telescopically within the hollow member and withdrawable to an active position at right angles to the member to effect rotation of the member, said lever having an enlarged end to contact the member as stops and prevent separation of the lever from said member.

13. A hub having an axial bore to receive a shaft, a hollow screw member having a threaded engagement with the shaft and having a flange overlying an end face of the hub to hold the hub on the shaft, said member being rotatable relative to the hub, means confining the flange to prevent axial movement of the member relative to the hub, a lever positionable to an inactive position telescopically within said hollow member and withdrawable to an active position at right angles to the member to effect rotation of said member, and said lever including stop means preventing separation of the lever from said member.
